UNITED STATES PATENT OFFICE.

LOUIS CADENEL, OF PARIS, FRANCE.

ELECTROMAGNETIC LOCKING DEVICE.

1,304,453.

Specification of Letters Patent.

Patented May 20, 1919.

Application filed May 27, 1914. Serial No. 841,337.

To all whom it may concern:

Be it known that I, LOUIS CADENEL, a citizen of the French Republic, residing at Paris, in France, have invented certain new and useful Improvements in Electromagnetic Locking Devices, of which the following is a specification.

This invention relates to improvements in electric locking devices.

10 In the improved device the locking members, in the form of bolts, are actuated and displaced by means of an electromagnet of particular construction; the device can be combined with a switch provided with secret 15 combination means so as to prevent unlocking of the device except by authorized persons.

The annexed drawings illustrate the invention.

20 Figure 1 is a section of a locking device applicable to motor cars.

Fig. 2 is a diagram illustrating the principle of the invention.

Fig. 3 is a side view of Fig. 2.

25 Fig. 4 is a plan view of Fig. 2.

Referring to Fig. 2. A—B indicates an electric coil wound around a tube *d* of non-magnetic metal in the center of which is fixed a soft iron core *c*; if in each of the 30 open ends of the tube *d* a slidable rod *t*¹ *t*² is introduced and current is passed through the coil capable of producing in the soft iron core *c* of the coil a negative pole on the side A and a positive pole on the side B for 35 example, the rods *t*¹ and *t*² and the soft iron core *c* will all be magnetized and each will have its positive and negative pole as indicated in the drawing.

It can be seen that by this arrangement 40 the magnetized fixed core *c* increases the action of the coil A—B on the slidable rods *t*¹ *t*², its magnetic power being additional to the action of the coil.

Such electromagnetic device can be applied in various ways to different systems 45 of locking devices without changing the principle of the invention.

The locking device for motor cars shown in Figs. 1 to 3 comprises a casing 1 which 50 is fixed in a suitable manner to a member 2 of the frame of the car and in which a box 3 can be introduced, said box containing a coil 4, in the central open space 4^a of which is a piece of soft iron 4^b, and movable bars 5 and 6 integral with respective arms 7 and 8 articulated on pins 9 and 10

mounted in the box. These arms are curved as shown in the drawing and their noses 7^a and 8^a traverse openings 6^a in the lateral walls of the box 3 and can engage in notches 11 and 12 suitably arranged on the wall of the casing 1.

A spring 13 connects the lower ends of the arms 7 and 8.

The bottom 14 of the box 3 is traversed by a rod 15 guided in a collar 16 and provided with a retracting spring; at the time of locking this rod moves into one of the recesses 18 of a disk 19 fixed for example on a shaft 20 to prevent the said shaft from transmitting movement, that is to say, to prevent the starting of a motor car or any other machine.

The coil 4 is arranged in a suitable electric circuit comprising a battery and contact button and can be combined with a suitable switch having secret combinations and housed in the space S and operated by the buttons B for example (Figs. 3 and 4).

In Fig. 1 the arms 7 and 8 and the bars 5 50 and 6 are shown in full lines in their locking position and in dotted lines in their unlocked position.

The device diagrammatically illustrated in Fig. 1, if cut through the middle, would 55 form two distinct coils which would each have at one end a fixed soft iron core and at the other end a movable bolt and which could be arranged in any desired position.

What I claim as my invention and desire 60 to secure by Letters Patent of the United States is:—

1. In an electromagnetic locking device, the combination of a casing, a removable box adapted to be set within said casing, a coil located within said box and adapted to receive electric current, a movable member or armature of magnetizable material arranged adjacent to said coil to be within its attractive influence when the coil is energized, a pivoted arm connected with said armature and having a curved end adapted to pass through a slot in the wall of said box and to project into a recess in the wall of said casing, a spring connected with said arm and tending to throw the armature away from the coil, a rotary recessed disk located adjacent to said casing, and a spring-pressed bolt carried by said box and adapted for locking engagement with said disk at a 105 recess thereof when the box is locked within the casing by said pivoted arm.

2. In an electromagnetic locking device, a casing, a removable box adapted to be set within said casing, an electromagnetic actuating device located in the box, two locking arms movable in said box and adapted to project therefrom into locking engagement with the casing, said arms being retracted when the said device is energized, to release the box from the casing, a spring connected with both arms and tending to throw them into the projecting or locking position, a disk mounted to turn, and a spring-pressed bolt carried by said box and adapted for locking engagement with said disk when the box is locked within the casing by said arms.
3. In an electromagnetic locking device, a casing, a removable box adapted to be set within said casing, an electromagnetic actuating device located in the box, two locking arms carried by said box movably and

adapted to project therefrom at opposite sides into locking engagement with the casing, said arms being spring-pressed to throw them into the locking position, and under the influence of said device, when energized, to shift them to the releasing position, a spring-pressed bolt carried by said box at a point equidistant from said locking arms, and a disk mounted to turn and adapted for locking engagement with said bolt when the box is locked to the casing by said arms.

In witness whereof I have signed this specification in the presence of two witnesses.

LOUIS CADENEL.
